UNITED STATES PATENT OFFICE.

OWEN C. FROM, OF NEW YORK, N. Y., ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

Application filed October 29, 1923. Serial No. 671,370.

The present invention relates to telephone exchange systems and more particularly to systems in which automatic switches are employed for establishing connections.

5 The object of the invention is to provide improved means for transferring records from one part of the system to another in systems where designations are recorded on controlling equipment.

10 In particular, the object of the invention is to provide an improved arrangement of relays whereby such designations may be transferred by means of code impulses transmitted over a loop circuit.

15 A feature of the invention lies in supplying potential to the conductors of the impulse circuit at all times, and in producing the impulses by either boosting or short-circuiting said potential.

20 A further feature of the invention lies in an arrangement for feeding a series of impulses of alternate polarity to said loop circuit and modifying the impulses to produce the codes by means of parallel circuits controlled by the settings of the registers.

25 A further feature of the invention lies in the manner of preparing these parallel circuits in advance of the period at which they become effective.

30 A still further feature of the invention lies in discharging the circuit during periods when no impulses are sent out.

35 Other features contemplated by this invention will be more thoroughly understood from a consideration of the following description and also from the appended claims.

40 A more specific discussion of the above features will be given in connection with the detailed description of the operation of the portions of the circuits in which they are involved.

45 In the drawings, Figs. 1 to 9, when arranged in the order illustrated in the diagram of Fig. 10, disclose as much of a telephone exchange system incorporating the features of the invention as is necessary for a thorough understanding thereof.

50 Fig. 1 illustrates in schematic manner a calling subscriber's line and a line switch of the coordinate type for extending the lines to outgoing trunks. This figure also shows diagrammatically a sender selector switch of the coordinate type.

Fig. 2 shows a portion of the detailed cir-

cuits of one of the trunks outgoing from the 55 line switch of Fig. 1 and also a diagram of a coordinate group selector switch in which said trunk terminates.

Figs. 4, 5, 8 and 9, taken together, show one of a number of register sender controlling mechanisms which are associable with the trunks by means of the sender selector switch illustrated in Fig. 1.

Fig. 4 illustrates the counting relays and other control relays of the sender. Fig. 8 65 shows the controlling relays and circuits for sending code impulses representing the recorded designations. Figs. 5 and 9 show relay registers on which designations are recorded under the control of the calling 70 subscriber's line.

Fig. 3 illustrates the incoming end of an interoffice trunk circuit. This trunk appears in a cord circuit at a manual operator's position in the called office. This figure also 75 shows a called subscriber's line terminating at a manual office.

Figs. 6 and 7 show a register circuit serving the purpose of a call indicator.

Fig. 11 shows a chart indicating the character of impulses transmitted for the digits 0 to 9, inclusive.

The line switch 100, the group selector switch 200, and the sender selector switch 110 are of the coordinate type such as shown 85 and described in detail in the Patent No. 1,507,140, granted September 2, 1924 to J. N. Reynolds.

The calling subscriber on initiating a call has his line automatically extended by way 90 of the line switch 100 to an idle trunk such as the trunk 103 terminating in the group selector or district selector switch 200. At the same time, the trunk 103 is associated with an idle register sender by means of the 95 sender selector switch 110. Following this, the subscriber dials a number of digits which are recorded on the several registers of the associated sender. Thereafter in any suitable manner, the register sender determines the 100 selective operation of the district selector switch 200 and an idle trunk is selected leading to the distant manual office in which the wanted line appears. Inasmuch as the present invention is not concerned with the detailed operation of the selector switches nor with the manner in which the register sender 105 exercises its control over the switches, sev-

5 several elements have been illustrated in schematic fashion. For a more detailed explanation of the way in which the operating circuits of the various switches function and 10 the manner in which the register senders control the selection of trunks, reference is made to the Patent 1,517,331, granted December 2, 1924, to S. B. Williams.

15 After a trunk has been selected by the switch 200 in the mechanical office leading to the distant manual office illustrated in Figs. 3, 6 and 7, it is next necessary to transfer the record established in the register sender over the trunk to the distant office to bring about the operation of the call indicator 20 in order that the operator may be advised of the called line number. This is accomplished by means of the equipment shown in Fig. 8 wherein the relay device 25 30 35 40 45 50 55 60 65 70 75 80 85 90 95 100 105 110 115 120 125 130 135 140 145 150 155 160 165 170 175 180 automatically and the trunk 103 is connected to the idle register sender shown in the drawing.

During the operation of the sender selector switch 110 a circuit may be closed in any suitable manner for the relay 204. Relay 204 operates and applies ground potential to the holding or sleeve conductor 111. As soon as the sender selector switch 110 is operated, it may complete a circuit in any suitable manner for relay 203. Relay 203 closes a substitute circuit for the slow releasing relay 204. The slow releasing character of relay 204 and other similar relays throughout the drawings has been indicated by weighted arrows across the armatures of such relays. The application of arrows pointing in opposite directions as applied to relays such as 807 and 808 indicates that such relays are both slow to operate and slow to release. Relay 203 also extends the tip and ring conductors of the trunk through the sender selector 110 to the selector sender. An impulse circuit is now traceable from battery through right winding of relay 400 in the sender, inner normal contact of relay 401, conductor 418, inner left contact of relay 411, through selector 110, conductor 220, inner lower contact of relay 203, conductor 105, through the line switch 100, over the loop of the calling line and returning through the line switch 100 to the conductor 104, inner upper contact of relay 203, conductor 221, through the selector 110, outer left contact of relay 411, outer contact of relay 401, left winding of coil 402 to ground. Relay 400 closes a circuit for slow release relay 404 which in turn closes a circuit for relay 410. Relay 410 applies holding ground to conductor 420 which provides holding circuits for the sender selector switch 110 and for relay 203 in the trunk circuit. Relay 400 also closes a circuit through the left winding of relay 403, which relay operates and closes a circuit for relay 425 extending from battery, left winding of relay 403, inner left contact of relay 403, outer left contact of relay 422, outer right back contacts of relays 422, 423 and 424, outer left front contact of relay 425, through both windings of relay 421 in series to ground. This circuit is ineffective at this time due to the direct connection from the left winding of relay 403 to ground through front contact of relay 400.

The apparatus is now in condition for receiving the first series of impulses. The operation of counting relays of this character forms the subject matter of applicant's 5 Patent No. 1,563,738, issued December 1, 1925.

The calling subscriber now manipulates his dial or other impulse transmitter to send a series of two impulses or interruptions of 10 the impulse circuit. In response to the first interruption of the circuit, relay 400 releases and permits the above traced circuit for relay 421 to become effective, whereupon relay 421 operates and locks in a circuit from 15 ground through its right winding, conductor 413, left contact of relay 412, conductor 409, resistance 405 to battery. Relay 421 also closes a circuit from conductor 413, inner right contact of relay 425, through the left 20 winding of relay 425, inner left contact of relay 421 to ground through the right winding of relay 403, the current in which circuit opposes that in the locking circuit for relay 425 and releases relay 425 differentially. 25 The locking circuit for relay 421 is in shunt of the energizing circuit through the left winding of relay 403 and tends to release relay 403. The circuit through the right winding of relay 403 which releases relay 30 425, is differential to the circuit through the left winding of relay 403, so that with relay 400 released, relay 403 releases quickly upon the operation of relay 421.

At the time relay 400 falls back in response 35 to the first impulse, a circuit is closed from ground through the back contact of relay 400, right contact of relay 404, winding of relay 406 to ground. Relay 406 operates and opens the initial energizing circuit for relay 425. It also closes an obvious circuit for 40 relay 408. Relay 408 operates and locks in a circuit from battery, winding and inner left contact of relay 408, outer right contact of relay 412, outer left contact of relay 410 to ground. Relay 408 closes circuits, 45 the purpose of which will be made clear hereinafter.

At the end of the first interruption, relay 400 again attracts its armatures and relay 403 is operated and completes a circuit for relay 422 by way of grounded battery, left winding and inner left contact of relay 403, outer right front contact of relay 421, outer right back contact of relays 423 and 424, outer left back contact of relay 425, through both windings of relay 422 in series to ground. Relay 422 does not operate, being shunted. Relay 406 being slow to release does not retract its armatures during this 50 time.

At the next interruption of the circuit, relay 400 falls back, permitting relay 422 to operate in series with the left winding of relay 403. Relay 422 operates and locks to 55 battery over conductor 413 and closes a

differential releasing circuit for relay 421 extending from ground through the right winding of relay 403, inner left contact of relay 422, left winding of relay 421, inner right contact of relay 421 to conductor 413. 70 Relays 421 and 403 release.

At the close of the second impulse, relay 400 remains energized long enough to permit relay 406 to deenergize and retract its armatures. Since relay 408 is operated, a 75 circuit is closed from ground, right normal contact of relay 406, inner right contact of relay 408, inner right contact of relay 412, conductor 416, right back contact of relay 901, winding of relay 902 to battery. Relay 80 902 attracts its armatures and locks in a circuit including its inner upper contact, conductor 903, winding of relay 412, and thence over the above traced circuit to ground at the right normal contact of relay 406. Relay 412, being shunted by the original circuit for relay 902, does not energize at this time. Relay 902 extends conductors 419, 429, 439, 449 to the relays of thousands register 900. Since relay 422 is the only 90 counting relay operated, a circuit may be traced from ground at the outer left contact of relay 410, conductor 417, outer right contact relay 412, conductor 415, outer right back contact of relay 425, outer left back 95 contact of relays 424 and 421, conductor 429, next to the innermost lower contact of relay 902, winding of relay 904, winding of relay 905 to battery. Relays 904 and 905 operate and lock in a circuit from battery, 100 windings of the two relays, inner right contact of relay 904, conductor 906, conductor 907, conductor 426, outer right contact of relay 410 to ground. Relay 905 closes an obvious circuit for relay 901 from grounded conductor 906 which relay operates and locks to grounded conductor 906. At its contact, relay 901 opens the shunt around the winding of relay 412 permitting that relay to 105 energize in series with relay 902. Relay 412 at its left armature, opens the locking circuit of the counting relays and at its outer right contact the locking circuit of relay 408. The counting relays are restored to normal. Relay 408 releases and opens the 110 circuit of relays 412 and 902, disconnecting register 900 from the counting relays. As soon as relay 412 falls back, the original circuit for relay 425 is closed and that relay energizes and prepares a circuit for relay 115 421 as before.

The subscriber next dials the second digit of the called number, that is "5". In response to the first interruption of the circuit, relay 406 is energized, in turn 120 energizing relay 408 relay 421 is operated and relay 425 released. In response to the next interruption of the circuit, relay 422 operates and relay 421 releases. In response to the third interruption of the circuit, relay 125 130

423 is energized in a circuit from battery, left winding of relay 403, inner left contact of relay 403, outer right back contact of relay 421, outer right front contact of relay 422, through both windings of relay 423 in series to ground. Relay 423 attracts its armatures and releases relays 422 and 403, in a manner similar to that for the other counting relays. In response to the fourth interruption of the circuit, the circuit prepared for relay 424, extending from battery through the left winding and inner left contact of relay 403, outer right back contact of relays 421 and 422, outer right front contact of relay 423, through both windings of relay 424 in series to ground, becomes effective and relay 424 attracts its armatures, releasing relays 423 and 403 and locking to conductor 413. The fifth interruption of this circuit causes the operation of relay 425 in a circuit from battery through the left winding and inner left contact of relay 403, outer right armatures and back contacts of relays 421, 422 and 423 outer right armature and front contact of relay 424, the two windings of relay 425 in series, to ground. Relay 425 locks to conductor 413 through its right winding and releases relays 424 and 403. Relay 425 also completes a circuit from battery, winding of relay 427, right back contact of relay 428, outer right contact of relay 408, outer right front contact of relay 425, conductor 415, outer right contact of relay 412, conductor 417, outer left contact of relay 410 to ground. Relay 427 attracts its armatures and locks in a circuit through the winding of relay 428 and the right contact of 427 to grounded conductor 415. Relay 428 cannot operate, being shunted by the energizing circuit of relay 427. When, now, at the close of this series of impulses, relay 400 remains energized for a considerable period of time, relay 406 releases and completes a circuit from ground, right back contact of relay 406, inner right contact of relay 408, inner right contact of relay 412, conductor 416, right front contact of relay 901, right back contact of relay 927, winding of relay 908 to battery. Relay 908 operates and locks in a circuit including its inner upper armature, conductor 903, winding of relay 412, inner right contact of relay 408 to ground at the right back contact of relay 406. Relay 508 extends conductors 419, 429, 439, 449 to register 909. Since relays 425 and 427 are operated, a circuit may be traced from ground at the outer left contact of relay 410, outer right contact of relay 412, conductor 415, outer right front contact of relay 425, outer right contact of relay 408, inner left contact of relay 427, inner left contact of relay 428, conductor 449, lowermost contact of relay 908, winding of relay 910 to battery. Relay 910 operates and locks by way of conductor 911 to grounded conductor 907. Relay 910 also connects ground from conductor 911, outer right contact of relay 910, winding of relay 927 to battery. Relay 927 operates and locks to conductor 70 911. The operation of relay 927 opens the energizing circuit for relay 908, which was in shunt of the winding of relay 412 and relay 412 operates. Relay 412 opens the locking circuit for the counting relays and 75 that of relay 408. Relay 408 in releasing opens the circuits of relays 412 and 908 whereupon these relays also release and the circuits of Fig. 4 are ready to receive the next set of impulses. 80

Relay 400 being energized at the time, as soon as relay 408 closes its outer left back contact, the previously traced circuit for relay 425 is closed and that relay prepares a circuit for relay 421 as before. The calling subscriber now manipulates his dial to send a series of three impulses. Relays 406 and 408 are operated at the first interruption of the circuit and at the end of the third interruption of the circuit, relay 423 is operated and the other counting relays de-energized. Relay 400 remaining energized for a considerable period permits relay 406 to release. A circuit is closed from ground at the right back contact of relay 406, inner right contact of relay 408, inner right contact of relay 412, conductor 416, right front contacts of relays 901, and 927, right back contact of relay 501, winding of relay 502 to battery. Relay 502 operates and locks 95 in a circuit through its inner upper contact, conductor 903, winding of relay 412, inner right contact of relay 408 to ground at the right back contact of relay 406. Relay 502 extends conductors 419, 429, 439, 449 to the 100 relays of register 500. Since relay 423 alone is energized, a circuit may be traced from ground at the outer left contact of relay 410, conductor 417, outer right contact of relay 412, conductor 415, outer right back contact of relay 425, outer left back contact of relay 424, outer left front contact of relay 423 conductor 419, innermost lower contact of relay 502, winding of relay 503 to battery. A circuit may also be traced from 105 grounded conductor 415, outer right back contact of relay 425, outer left back contact of relay 424, outer left back contact of relay 421, conductor 429, next to the innermost lower contact of relay 502, winding of relay 504 to battery. Relays 503 and 504 operate and lock by way of conductor 505 to grounded conductor 907. The operation 110 of these relays also extends ground from conductor 505 to relay 501 which relay operates and locks to conductor 505. The operation of relay 501 opens the energizing circuit of relay 502 permitting relay 412 to energize and bring about the release of the 115 counting relays as before. 120

The calling subscriber next operates his dial to send a single impulse, which represents the fourth and last digit of the called number. In response to this impulse, relay 421 is operated and relay 425 released. At the completion of the impulse, relay 406 releases and a circuit is completed from ground, outer right back contact of relay 406, inner right contact of relay 408, inner right contact of relay 412, conductor 416, right front contacts of relays 901, 927 and 501, right back contact of relay 506, winding of relay 507 to battery. Relay 507 operates and locks by way of its inner upper contact, conductor 903, winding of relay 412 and thence over the previously traced circuit to ground. Due to the energization of relay 421, a circuit is closed from grounded conductor 415, outer right back contact of relay 425, outer left back contact of relay 424, outer left front contact of relay 421, conductor 419, innermost lower contact of relay 507, winding of relay 508 to battery. Relay 508 operates and locks by way of conductor 509 to grounded conductor 907. In addition, relay 508 closes an obvious circuit for relay 506. Relay 506 operates and locks to conductor 509. Relay 506 in operating opens the circuit in shunt of the winding of relay 412 and this relay energizes and brings about the restoration of the counting relays and the disconnection of register 510 from the energizing leads.

After the subscriber has set up the record on the sender, the district selector switch 200 is operated to seize an idle trunk 207 outgoing to the distant called office. During the operation of switch 200, relay 206 is operated and locks through its inner upper contact, conductor 210, upper contact of relay 203, to the grounded conductor 111. Upon the operation of relay 206, relay 205 is operated by the switch 200 in a suitable manner and locks through its left armature to conductor 210.

After the connection has been extended to the distant office, the apparatus is placed in condition to transmit code impulses over the trunk in accordance with the settings of the numerical registers in Figs. 5 and 9 to operate the call indicator in the distant office. When the apparatus is ready for this purpose a circuit is completed in any suitable manner for relay 800. The manner in which the above mentioned operations take place is shown and described in detail in the Patent No. 1,517,331, granted December 2, 1924 to S. B. Williams. Relay 800 closes a circuit from battery through the winding of relay 801, contact of relay 800, conductor 802, middle left contact of relay 506 to ground. Relay 801 operates and locks through its inner left contact, conductor 430 to ground at the inner right contact of relay 410. Relay 801 connects the

relay 803 to the tip and ring conductors of the line resulting in a circuit as follows: battery through the inner lower back contact of relay 300 (Fig. 3) conductor 301, right winding of relay 302, winding of relay 70 303, inner normal contact of relay 304, outer back contact of relay 305, thence over the tip side of trunk 207 through switch 200, uppermost front contact of relay 208, inner right contact of relay 205, conductor 211, 75 through the selector switch 110, conductor 431, outer left contact of relay 801, conductor 825, right normal contact of relay 812, conductor 832, outer right back contact of relay 805, winding of relay 803, left back 80 contact of relay 805, middle left contact of relay 801, conductor 432, through the switch 110, conductor 212, outer right contact of relay 205, lowermost front contact of relay 206 through the switch 200 thence over the 85 ring side of the line, inner back contact of relay 305, outer normal contact of relay 304, left winding of relay 302 to ground. Relays 303 and 302 operate and relay 302 closes a circuit for relay 306. Relay 306 operates 90 and at its outer left contact closes a circuit around relay 303 releasing this relay and preventing it from reoperating in series with the right winding of relay 302. Relay 306 also closes a circuit from battery through 95 the assignment lamp 307, lower winding of relay 308, outer right back contact of relay 309, upper inner contact of relay 308, right inner contact of relay 306 to ground. Lamp 307 lights to advise the operator that a call 100 is awaiting attention on the incoming trunk 207. Due to the character of relay 308, however, it is not energized sufficiently to attract its armature.

The code impulses are sent to the receiving office over a full metallic circuit comprising both tip and ring conductors of the line in series. These impulses may be of either positive or negative polarity dependent upon the side of the line circuit to which the positive pole of battery is connected. They may also be weak or strong, dependent upon whether battery is fed to the line through a high or low resistance. The impulses are received by the relays 600, 601 115 and 602. Relay 600 is polarized in such a manner as to respond only to the current produced when the positive pole of battery is connected to the tip side of the line. Relay 601 is polarized in such a manner as 120 to respond to current of the opposite polarity. Both relay 600 and 601 respond either to strong or weak impulses provided the polarity is in the proper direction. Relay 602 responds to strong impulses of either 125 polarity but does not respond to weak impulses.

At the time the above traced circuit is closed, relay 803 in the mechanical office also operates and closes a circuit including relays 130

302, 303 and 803 from battery through winding of relay 809, front contact of relay 803 to ground. Relay 809 closes a circuit from battery, winding of relay 804, front contact of relay 809 to conductor 430 and ground at the inner right contact of relay 410. Relay 804 operates and locks through its inner right contact to conductor 430.

Returning to the called office, the operator observing the illumination of lamp 307 presses the individual assignment key 310 to associate the call indicator with the trunk 207. Key 310 closes a circuit from battery through the winding of relay 605, lower contact of relay 308, right winding of relay 309, upper contact of key 310, contact of relay 606 to ground at the right back contact of relay 607. A branch of this circuit also extends through the winding of relay 626 to ground but the direct path to ground shunts this relay and prevents its operation at this time. Relay 309 operates and locks in a circuit from battery through winding of relay 605, lower contact of relay 308, windings of relay 309 to ground at its left contact. Relay 309 opens the original circuit of lamp 307 and connects this lamp in series with the interrupter 311. The lamp flashes during the period that impulses are being received and until the operator later inserts the plug of the cord circuit in the jack of the called line. Relay 309 also closes a circuit from battery through the winding of relay 305 and in parallel through the left winding of relay 312, inner right contact of relay 309, winding of relay 606 to ground at the left back contact of relay 607. Relay 305 operates and extends the tip and ring conductors of the incoming trunk to conductors 604 and 603, respectively. When relay 305 operates it opens the circuit including relays 302 and 803. Relay 302 releases and opens the circuit of relay 306 which also deenergizes. Relay 803 in releasing, permits the release of relay 809 which relay completes a circuit from battery through the winding of relay 805, outer right contact of relay 804, back contact of relay 809 to grounded conductor 430 in which circuit relay 805 operates.

Relays 807 and 808 at the mechanical office cooperate with each other to measure intervals of time during which the code impulses are produced and propagated over the line circuit to the distant office. Due to the characteristics of these relays they operate and release slowly. Relays 810 and 811, 812 and 813, 814 and 815, and 831 operate in a definite sequence and their function is to measure a sufficient number of periods of code impulses to represent each of the different digits.

With relay 805 operated a circuit is closed from ground through the inner right contact of relay 805, conductor 817, thence

through the outer left contact of relay 901 and the outer upper contact of relay 912 and in parallel through the corresponding contacts of relays 927 and 913, 501 and 511, and 506 to conductor 513, through the right winding of relay 818 to battery. Relay 818 operates and locks in a circuit through its left winding, the outer left normal contact of relay 831 to ground at the left contact of relay 804. A second locking circuit also extends from the inner left contact of relay 818, through the normal contact of relay 815, conductor 822, back contact of relay 810 to the left contact of relay 804, and a third locking circuit is prepared which would extend through the right front contact of relay 813 and conductor 820 to the right contact of relay 818. These locking circuits have no function at this time since the energizing circuit is maintained, but at the release of the sender they serve to insure that relay 818 will not release until relays 810, 813 and 815 have all operated and released. With relay 818 energized, a circuit is closed from battery through resistance 821, winding of relay 807, right back contact of relay 811, right back contact of relay 813, conductor 820 to ground at the outer right contact of relay 818. Relay 807 energizes after an interval and closes a circuit from battery through resistance 819, winding of relay 808, outer right front contact of relay 807 to grounded conductor 820. Relay 807 also closes a circuit from battery through the winding of relay 813, outer left back contact of relay 812, conductor 829, middle contact of relay 807, conductor 820 to ground at the right contact of relay 818. Relay 813 operates and locks through the winding of relay 812, inner left contact of relay 813, conductor 822, back contact of relay 810, left contact of relay 804 to ground, and also through the inner left back contact of relay 815, conductor 840, outer left back contact of relay 831 to the ground at relay 804. These two circuits insure that relays 812 and 813 will not release until after both relays 815 and 810 have operated. Relay 812 does not operate at this time since it is shunted by the energizing circuit of relay 813. Relay 808 in operating closes a circuit from battery through resistance 821, outer contact of relay 808, to the grounded conductor 820. This circuit shunts relay 807 which starts to release after an interval. Relay 807 becomes deenergized and a circuit is closed from battery through resistance 819, outer right back contact of relay 807 to grounded conductor 820. This circuit shunts relay 808 which, after an interval, releases its armatures.

As soon as relay 818 is operated, a circuit is closed for sending the first impulse of the code representing the first digit of the number of the wanted subscriber. This circuit

may be traced from ground which represents the positive pole of battery, outer right contact of relay 805, conductor 832, right normal contact of relay 812, conductor 825, 5 outer left contact of relay 801, conductor 431, through selector switch 110, conductor 211, inner right contact of relay 205, upper front contact of relay 206 through the district selector switch 200, thence over the tip 10 side of the line, outer front contact of relay 305, conductor 604, through the relays 600, 601, and 602, conductor 603, inner front contact of relay 305 over the ring side of the line, through the selector switch 200, lower 15 front contact of relay 206, outer right contact of relay 205, conductor 212, through the selector switch 110, conductor 432, middle left contact of relay 801, left front contact of relay 805, conductor 824, left normal 20 contact of relay 812, conductor 833, outer left contact of relay 818, high resistance 836 to battery. The current in this circuit is in the direction to cause the operation of relay 600, but since relay 914 of the thousands 25 register 900 is not operated, a circuit is closed from ground, conductor 916, inner left contact of relay 914, inner upper back contact of relay 912, conductor 835, right back contact of relay 815 to conductor 833. 30 This ground shunts the battery through resistance 836 and no impulse is sent out over the line. As soon as both relays 807 and 808 have deenergized, relay 812 operates in the locking circuit of relay 813, reversing 35 the connection of battery and ground to the impulse circuit and preparing a circuit for relay 811.

It might be well at this time to indicate how a common battery and a common ground is connected to the impulse circuit. The connections from battery extend through resistance 836, the outer left contact of relay 818, conductor 833 and the left normal contact of relay 812 to the ring side 40 of the line and also through resistance 827 and conductor 826 to the inner right armature of relay 812, so that when relay 812 is operated, battery is connected through the right alternate contact of that relay to the tip side of the line. The connections from the common ground extend either by way 45 of conductor 832 and the right normal contact of relay 812 to the tip side of the line or when relay 812 is operated by way of conductor 823 and the left alternate contact 50 of relay 812 to the ring side of the line.

Relay 808, in releasing, opens the shunt around relay 807 which, after an interval, attracts its armatures and in turn closes the 55 operating circuit of relay 808. Relay 808 operates after an interval of time. While relays 807 and 808 are undergoing energization and deenergization, a circuit is closed as follows for transmitting a second code impulse over the line: From ground

through outer right contact of relay 805, conductors 832 and 823, left alternate contact of relay 812, conductor 824, left front contact of relay 805, middle left contact of relay 801, conductor 432 thence over the 60 above traced impulse circuit back to conductor 431, outer left contact of relay 801, conductor 825, right alternate contact of relay 812, conductor 826, high resistance 827, to the negative pole of battery. The 65 current in this circuit would produce a weak impulse in the direction to operate relay 601. However, since relay 904 is operated, a path in parallel with the high resistance 827 is closed which may be traced by way of the right back contact of relay 814, conductor 828, inner lower back contact of relay 912, inner left contact of relay 904, low resistance 915 to battery. Due to this path 70 from battery through low resistance 915, the impulse transmitted is heavy and marginal relay 602 is also operated. The operation of relay 601 closes a circuit from battery 75 through left windings of relays 608 and 609, left back contact of relay 608, conductor 610, contact of relay 601, conductor 611, left contact of relay 605, outer left contact of relay 612 to ground. Relay 609 operates but relay 608 being marginal remains inert. Relay 608 completes a circuit from battery 80 through the left windings of relays 608 and 609, right winding of relay 608, inner right contact of relay 609, conductor 613 to grounded conductor 611. Relay 608, however, does not operate since its right winding is shunted by the previously traced circuit. Relay 609 closes a circuit from 85 grounded conductor 613, outer right contact of said relay, left back contact of relay 614, winding of relay 615 to battery. Relay 615 90 operates and closes a locking circuit from battery through its winding and the winding of relay 614, inner right contact of relay 615 to grounded conductor 613. Relay 614, however, being shunted does not operate at this 95 time. Another circuit is closed from grounded conductor 611, contact of relay 602, outer right back contact of relay 608, inner right back contact of relay 614, conductor 616, left winding of register relay 700 to battery. Relay 700 locks in a circuit through its windings and inner right contact, conductors 701 and 702, right contact of relays 605 to ground at the right contact of relay 612. 100

When relay 807 operates as above explained, it closes a circuit from battery, winding of relay 811, outer left front contact of relay 812, conductor 829, middle contact of relay 807 to grounded conductor 820. Relay 811 operates and locks through winding of relay 810, inner left contact of relay 811 to ground at the outer left contact of relay 813. Relay 810 does not operate in this circuit as it is shunted. Relay 811 in operating, closes a circuit from grounded 105 110 115 120 125 130

battery, winding of relay 815, outer left back contact of relay 814, conductor 830, outer left contact of relay 811, outer left contact of relay 813 to ground. Relay 815 5 operates and locks in a circuit through the winding of relay 814, inner left front contact of relay 815, outer left back contact of relay 831 to ground at the left contact of relay 804. Relay 814 does not operate at 10 this time, being shunted.

Relays 807 and 808 are next deenergized in succession in the manner above explained. As soon as relay 808 is deenergized, the shunt around relay 810 is removed and that 15 relay energizes in the locking circuit of relay 811. Relay 810 in operating opens the locking circuit for relays 813 and 812 which release, in turn opening the locking circuit for relays 810 and 811 which also release. 20 The release of relay 811 opens the energizing circuit for relay 815 and permits relay 814 to energize in the locking circuit of relay 815. The operation of relay 814 closes a circuit from grounded battery, winding 25 of relay 912, outer upper contact of relay 918, conductor 838 to ground at the inner right contact of relay 814. Relay 912 energizes and locks in a circuit through the winding of relay 918, the lowermost contact 30 of relay 912, conductor 839 to ground at the right contact of relay 801. Relay 918 does not operate at this time, being shunted.

The release of relay 812 reverses the direction of current in the impulse circuit and 35 permits relay 601 to release. The energizing circuit of relay 609 is opened and relay 608 operates in the locking circuit which was previously traced.

During the next energization and deenergization of relays 807 and 808, the impulse circuit is closed from ground at the outer right front contact of relay 805, conductor 40 832, normal contact of relay 812, conductor 825, outer left contact of relay 801 to conductor 431 and thence as above traced back to conductor 432, middle left contact of relay 801, left front contact of relay 805, conductor 824, left normal contact of relay 812, conductor 833, outer left contact of relay 818, 45 50 resistance 836 to battery. Since relay 917 is not operated a shunt to ground is completed from conductor 833 by way of the right front contact of relay 815, conductor 837, inner upper back contact of relay 918, 55 inner left back contact of relay 917 to ground. Therefore, no impulse may pass out over the line. Meanwhile, the energization of relay 807 has caused the energization of relay 813 which relay locks as before. 60 When now relays 807 and 808 deenergize, relay 812 energizes in the locking circuit of relay 813.

During the next energization and deenergization of relays 807 and 808 the fourth and 65 last impulse of the code of the first digit is

sent. The impulse circuit may be traced from ground at the outer right front contact of relay 805, conductors 832 and 823, left alternate contact of relay 812, conductor 824, left front contact of relay 805, middle contact of relay 801, conductor 432, thence through relays 600, 601 and 602 and back to conductor 431, outer left contact of relay 801, conductor 825, right alternate contact of relay 812, conductor 826, resistance 827 to grounded battery. Since resistance 827 is a high resistance and, due to the deenergized condition of relay 924, no parallel path is closed to battery through low resistance 915, the impulse sent out over the line is weak and of such a direction that relay 601 is operated. Relay 601 applies ground potential to conductor 610 whereby relay 609 is shunted and releases while relay 608 remains locked through its left winding. 55 Relay 609 removes the shunt from relay 614 but that relay remains shunted at the inner right contact of relay 608.

As soon as relay 811 operates, relay 814 being operated, a circuit is closed for relay 90 831 extending from battery through the left winding of that relay, left front contact of relay 814, conductor 830, outer left contact of relay 811 to ground at the outer left contact of relay 813. Relay 831 operates 95 and locks in a circuit through its left winding, inner left contact to ground at the outer left contact of relay 813. Relay 831 opens the locking circuit for relays 814 and 815 but they are held operated as long as relay 813 100 remains operated. With relays 807 and 808 deenergized, the energizing circuit of relay 811 is opened and relay 810 is energized in series with relay 811. Relays 815 and 810 both being operated, no locking circuit may 105 be found for relays 813 and 812 and these relays release, in turn releasing relays 810 and 811 and relays 814 and 815. The deenergization of relay 814 opens the energizing circuit for relay 912 and permits relay 918 110 to operate in the locking circuit of that relay. When relay 912 energized, two of the leads connecting the impulse mechanism with the register 900 were transferred to register 909 and now that relay 918 is 115 operated, the second pair is transferred. The release of relay 812 again reverses the direction of current in the impulse circuit so that relay 601 releases opening circuit of relay 608. Relay 608 deenergizes and 120 opens the shunt around relay 614, which relay operates in the locking circuit of relay 615. The apparatus is now ready to transmit the second digit to the distant office.

A consideration of the foregoing operations will show that the impulse circuit is the same for all pulses from one armature contact of relay 812 to the distant office and back to the other contact of that relay. Battery, through a high resistance, and 125 130

ground are fed to the contacts of this relay in such a manner that the positive pole of battery, represented by ground, is connected to the tip of the impulse circuit through 5 a normal contact of that relay and to the ring of the impulse circuit through an alternate contact of the relay. It is therefore apparent that the function of relay 812 is to reverse the direction of the current 10 in the impulse circuit. The contacts of this relay make their alternate arrangement before breaking their normal arrangement so that for a very brief interval ground is connected to both sides of the impulse circuit, 15 tending to clear it of any residual charge. At no time is the impulse circuit open at the contacts of relay 812. As far as the operation of relay 812 is concerned, alternate weak impulses of positive and 20 negative polarity would be produced, separated by a brief grounded interval.

In order to produce the code character of the impulses, parallel circuits are arranged under the control of the registers. 25 There is a register for each digit and in each register there is one relay corresponding to each impulse of the code of the corresponding digit. The relays corresponding to the positive impulses when deenergized, 30 close a parallel or shunt circuit to ground, which short circuits the positive pulse. The relays corresponding to the negative pulses when energized, close a parallel path to battery through a low resistance, which supplements the battery through high resistance ordinarily connected to the impulse circuit and causes a heavy impulse. When 35 deenergized, this parallel path is open and only a weak impulse reaches the impulse circuit. Thus, when none of the relays of the register are operated, no positive pulses and only weak negative pulses are sent, and according to which of the register relays are operated, weak positive impulses 40 or heavy negative impulses are sent.

The connection of the shunt circuits with the main impulse circuit is under the control of the relay combinations 912 and 918, 913 and 923, etc., and the relay combination 814 and 50 815. Relay 814 also controls the relay combinations 912 and 918, etc. The leads for controlling the first two impulses of a code group extend through the back contacts of the first one of each pair of relays, i. e. 912, 55 913, etc. The leads for controlling the second two impulses extend through the back contacts of the second one of each pair of relays, i. e. 918, 923, etc. The front contacts of these relays connect to the corresponding armatures of the next pair so that the energization of these relays serves to transfer the shunt leads from the control 60 of one register to that of the next.

Furthermore, the lead for controlling the 65 first positive impulse extends through the

back contact of relay 815 and that for controlling the second positive impulse through the front contact of that relay. Similarly, the lead for controlling the first negative impulse extends through the back contact 70 of relay 814 and the lead for controlling the second negative impulse extends through the front contact of that relay. The successive energizations of relay 814 cause the energization of the first relay of each successive pair of relays, namely 912, 913, 511 and 512, while the subsequent successive deenergizations of that relay permit the second relay of the corresponding pair, namely 918, 923, 516, and 520 to operate. 75 80

The cycle of operations, briefly, comprises the measurement of four intervals of time by the relay combinations 807 and 808. An interrupter of any well known type would serve as well to measure these time intervals. 85

At the beginning of the first interval, relay 813 operates and at the end relay 812 operates, reversing the impulse leads. At the beginning of the second interval, relay 811 operates, causing the operation of relay 815 90 which relay transfers the control of the positive impulse from the first to the third relay of the register involved. At the close of the interval, relay 810 operates, releasing relays 812 and 813, 811 and 810 and permitting 95 relay 814 to operate. The release of relay 812 returns the impulse circuit to its first condition, ready to send a positive pulse. Relay 814 causes the operation of relay 912 (or 913, etc.), transferring the first

two control leads to the next register. Relay 814 also transfers the control of the negative impulse from the second to the fourth relay of the register. At the beginning of the third interval, relay 813 100 operates again, the control of the positive impulse being at the front contact of relay 815. At the close of the interval, relay 812 operates again, reversing the impulse circuit, ready for a positive impulse which 105

is controlled through the front contact of relay 814. At the beginning of the fourth interval, relay 811 operates, causing the operation of relay 831. At the close of the interval, relay 810 operates and all seven 110

relays release ready for a new cycle. The release of relay 814 permits the energization of relay 918 (or 923, etc.), transferring the second pair of leads to the next register. 115

It is thus clear that this relay combination results in an impulse sending arrangement in which the impulses are transmitted over an uninterrupted impulse circuit; that the code arrangement of the pulses is under the control of registers; and that the control circuits are in all cases prepared in advance of the occasion on which they 120 may be called upon to function. 125

Since the codes corresponding to the va- 130

rious digits in some cases involve only one or perhaps no positive pulse, it is quite possible that several negative pulses may occur in succession, tending to charge the line so that when the impulse circuit is opened, as has been the custom heretofore, a discharge may take place sufficient to erroneously operate in the receiving circuit and cause false registrations at the distant office. The arrangement of the present invention overcomes this difficulty by maintaining the impulse circuit closed throughout the sending of the impulses and by short circuiting the positive pulses when none is desired, instead of opening the line.

Returning now to the operation of the circuits for sending the second digit, relays 807 and 808 again undergo energization and deenergization in succession and relay 813 is energized. The impulse circuit is closed through the normal contacts of relay 813 and battery through resistance 836 is shunted by a circuit from ground, conductor 919, right back contact of relay 920, uppermost 25 back contact of relay 913, inner upper front contact of relay 912, conductor 835, right back contact of relay 815 to conductor 833. When relays 807 and 808 deenergize, relay 812 energizes in the locking circuit of 30 relay 813 and reverses the impulse leads.

Since the relay 921 is not energized, no circuit is closed through low resistance 915 and only a light impulse is transmitted over the impulse circuit. This light negative impulse causes the operation of relay 601. Relay 601 places a ground potential on the conductor 610 and relay 609 operates in the manner above described. Relay 609 closes a circuit from ground over conductor 613, 40 through the outer right contact of relay 608, left front contact of relay 614, left back contact of relay 617, winding of relay 618 to battery. Relay 618 operates and closes a locking circuit for itself in series with relay 617 to grounded conductor 613. Relay 617 does not operate since it is shunted.

As soon as relay 807 is reenergized, relay 811 becomes energized and in turn causes the energization of relay 815. At the completion of the period, relay 810 energizes in the locking circuit of relay 811 and opens the locking circuit of relays 812 and 813 which release, in turn releasing relays 810 and 811, permitting relay 814 to operate in series with relay 815 as before described. The operation of relay 814 closes a circuit for relay 913 from battery, winding of relay 913, outer upper contact of relay 923, lower front contact of relay 918, conductor 638, inner right contact of relay 814 to ground. Relay 913 operates and locks in a circuit including the winding of relay 923, lowermost contact of relay 913 to grounded conductor 839. Relay 913 transfers the first two leads from the impulse

circuit to the next register. Relay 923 does not operate, being shunted.

The release of relay 812 causes the de-energization of relay 601 and the operation 70 of relay 608 in the locking circuit of relay 609 as before.

During the next energization and deenergization of relays 807 and 808, the impulse circuit is again closed through the normal contacts of relay 812 and due to the de-energized condition of relay 922, battery through resistance 836 is shunted by a circuit from grounded conductor 919, right contact of relay 922, inner upper back contact of relay 923, inner upper front, contact of relay 918, conductor 837, right front contact of relay 815 to conductor 833. In the meantime, relays 813 and 812 have been energized and locked in the manner previously described.

During the next energization and deenergization of relays 807 and 808, the impulse circuit is completed through the alternate contacts of relay 812, and due to the energized condition of relay 910, a path parallel to that from battery through high resistance 827 is completed from grounded battery through low resistance 915, through right contact of 910, inner lower back contact of relay 923, inner lower front contact of relay 918, conductor 841, outer right front contact of relay 814 to the impulse circuit as previously described. Due to this parallel path, the impulse transmitted, which is of such polarity as to cause the operation of relay 601 is also a heavy impulse and causes the operation of marginal relay 602. Relay 601 shunts relay 609 which releases but the shunt around relay 617 is maintained at the inner right contact of relay 608. Due to the energization of relay 602 a circuit is completed from grounded conductor 611, contact of relay 602, outer right front contact of relay 608, outer right front contact of relay 614, outer right back contact of relay 617, conductor 619, left winding of relay 703 to battery. Relay 703 operates and locks to grounded conductor 701.

Meanwhile relay 811 is operated and locked as before described and relay 831 is energized through its left winding, left front contact of relay 814, outer left contact of relay 811 to ground at the outer left contact of relay 813. Relay 831 operates and locks direct to the outer left contact of relay 813. At its outer left contact, relay 831 opens the locking circuit of relays 815 and 814 but these relays are held operated through the right front contact of relay 813. When relays 807 and 808 release, relay 810 energizes and opens the locking circuits for relays 813 812. Relays 813 and 812 release, in turn releasing relays 810 and 811 and relays 814 and 815. As soon as relay 813 releases, relay 831 releases. On the release of relay 120

814 the shunt is removed from the winding of relay 923 and that relay energizes in the locking circuit of relay 913. The release of relay 812 completes the impulse circuit through the normal contacts of that relay and relay 601 releases opening the circuit of relay 608 and permitting relay 617 to operate in the locking circuit of relay 618. The apparatus is now in condition for sending the impulses corresponding to the third or tens digit.

Relays 807 and 808 again undergo energization and deenergization. During this period a circuit is closed from the positive pole of battery over conductor 832, right normal contact of relay 812, conductor 825, outer left contact of relay 801, thence over the tip side of the line, returning over the ring side of the line through the middle left contact of relay 801, left front contact of relay 805, conductor 824, left normal contact of relay 812, conductor 833, outer left contact of relay 818, resistance 836 to grounded battery. Since relay 503 is operated, there is no shunt path to ground and a weak impulse is transmitted over the line in such direction as to cause the operation of relay 600. Relay 600 closes a circuit from grounded conductor 611, contact of relay 600, left back contact of relay 609, left front contacts of relays 615 and 618, outer left back contact of relay 620, conductor 621, left winding of relay 704 to battery. Relay 704 operates and locks through its windings to grounded conductor 702. When relay 807 operated, relay 813 operated and locked. When now relays 807 and 808 de-energize, relay 812 operates reversing the impulse circuit and relay 600 deenergizes.

Next, relays 807 and 808 energize and de-energize again. During this period a circuit is closed from the positive pole of battery over conductors 832 and 823, left alternate contact of relay 812, thence over the ring side of the line returning over the tip side of the line through the right alternate contact of relay 812 and in parallel through high resistance 827 to battery and through the back contact of relay 814, conductor 828, inner lower front contacts of relays 912 and 913, inner lower back contact of relay 511, left contact of relay 504, conductor 514 and low resistance 915 to the negative pole of battery. A heavy impulse is transmitted over the impulse circuit whereby relays 601 and 602 are operated. Relay 601 causes the operation of relay 609 whereupon a circuit is closed from ground over conductor 613 through outer right contact of relay 609, left front contacts of relays 614 and 617, left back contact of relay 622, winding of relay 620 to battery. Relay 620 operates and prepares a circuit for relay 622 but this relay does not operate, being shunted. Another circuit is closed from

grounded conductor 611, through contact of relay 602, outer right back contact of relay 608, inner right front contacts of relays 614 and 617, inner right back contact of relay 622, conductor 623, left winding of relay 705 to battery. Relay 705 operates and locks through its windings to grounded conductor 702. When relay 807 energizes, relay 811 energizes and prepares a circuit for relay 810. Relay 811 also completes a circuit for relay 815 which operates and prepares a circuit for relay 814. When relays 807 and 808 deenergize, relays 810 and 814 operate in series with relays 811 and 815 respectively. Relay 810 opens the locking circuit for relays 813 and 812 which relays deenergize. Relays 815 and 814 remain locked through the outer left contact of relay 831. The release of relay 812 reverses the impulse leads and permits the deenergization of relays 601 and 602. Relay 601 released, permits relay 608 to operate in series with relay 609. The operation of relay 814 closes a circuit from grounded battery, winding of relay 511, outer upper contact of relay 516, lowermost front contacts of relays 923 and 918, conductor 838 to ground at the inner right contact of relay 814. Relay 511 operates and locks in series with relay 516 and the lowermost contact of relay 511 to grounded conductor 839. Relay 516 does not operate, being shunted. It is to be noted that at this time the first two leads from the impulse circuit to the register have been transferred from the tens register to the units register.

Next, relays 807 and 808 energize and de-energize. During this period the impulse circuit is closed from battery through high resistance 836 to the left normal contact of relay 812 and thence over the ring side of the line and back over the tip side of the line to the right normal contact of relay 812 and to ground. Since relay 515 is not operated, a shunt circuit is completed from grounded conductor 916, left contact of relay 515, inner upper back contact of relay 516, inner upper front contact of relays 923 and 918, conductor 837, right front contact of relay 815 to conductor 833. Therefore, no impulse is permitted to pass out to the line and since the two sides of the line are grounded, any charge which may have accumulated due to impulses passing there-over will be discharged. When relay 807 attracted its armature, relay 813 operated and prepared a circuit for relay 812. When both relays 807 and 808 have deenergized, relay 812 operates in series with relay 813.

Next, relays 807 and 808 energize and de-energize in succession. An impulse circuit is completed through the alternate contacts of relay 812 from battery through high resistance 827 and back to ground. Since relay 517 is not operated, no path is avail-

able from battery through low resistance 915 and a weak impulse only is sent out over the line. Relay 601 operates and shunts relay 609 which relay deenergizes. On the energization of relay 807 relays 811 and 831 operate and on the deenergization of both relays 807 and 808, relay 810 operates causing in turn the release of relays 813 and 812, 815 and 814, 810 and 811, and 831. The release of relay 814 permits relay 516 to operate in series with relay 511. The release of relay 812 reverses the impulse circuit, releasing relay 601. Relay 601 opens the circuit for relay 608 which permits relay 622 to operate in series with relay 620. The operation of relay 516 has transferred the remaining two leads from the tens register to the units register. The apparatus is now ready for sending the fourth or units digit.

Relays 807 and 808 energize and deenergize in succession. Relay 813 operates. The impulse circuit is completed through the normal contacts of relay 812 and due to the energization of relay 508 no shunt is closed to battery. A weak impulse is sent over the line in the direction to cause the energization of relay 600. Relay 600 completes a circuit from grounded conductor 611 through its contact, left back contact of relay 609, left front contacts of relays 615, 618 and 620, conductor 624, left winding of relay 706 to battery. Relay 706 operates and locks to grounded conductor 702. When relays 807 and 808 deenergize, relay 812 operates in series with relay 813, reversing the impulse circuit and permitting relay 600 to release.

Relays 807 and 808 again energize and deenergize. Relay 811 energizes, in turn energizing relay 815. With relay 812 energized, the impulse circuit extends from positive pole of battery to the left alternate contact of relay 812, out over the ring side of the line and back over the tip side to the right alternate contact of relay 812, high resistance 827 and battery. Since relay 518 is not operated there is no path from battery through low resistance 915 to the impulse circuit and only a weak impulse is sent. This impulse causes the operation of relay 601 which relay closes a circuit for relay 609. Relay 609 operates and locks through the winding of relay 608 as before and, in operating, closes a circuit over grounded conductor 613, outer right front contact of relay 609, left front contacts of relays 614, 617 and 622, inner left contact of relay 625, winding of relay 626 to battery. Relay 626 energizes and closes a locking circuit for itself in series with relay 625. This latter relay remains deenergized since it is shunted. When relays 807 and 808 become deenergized, relays 810 and 814 operate in the locking circuits of relays 811 and 815 respectively. Relay 814 in operating closes

a circuit from grounded battery, winding of relay 512, middle upper contact of relay 520, lowermost contacts of relays 516, 923 and 918, conductor 838 to ground at the inner right contact of relay 814. Relay 512 operates and locks in a circuit including the winding of relay 520, lowermost contact of relay 512 to grounded conductor 839. Relay 520 does not operate, being shunted. Relay 810 opens the locking circuit of relays 813 and 814 and these relays release, in turn releasing relays 810 and 811. When relay 812 releases, the impulse circuit is reversed and relay 601 releases, permitting relay 608 to operate.

Relays 807 and 808 again energize and deenergize. Relay 813 operates and locks through the winding of relay 812 but relay 812 does not operate, being shunted. The impulse circuit now extends through the normal contacts of relay 812 and since relay 519 is not operated, a shunt circuit is completed from grounded conductor 916 through left contact of relay 519, inner upper contact of relay 520, inner upper front contacts of relays 516, 923 and 918, conductor 837, right front contact of relay 815 to conductor 833, preventing the transmission of an impulse over the impulse circuit. When relays 807 and 808 deenergize, relay 812 operates in the locking circuit of relay 813, reversing the impulse circuit which is now completed by way of the alternate contacts of relay 812.

Relays 807 and 808 again energize and deenergize. Relay 811 operates and causes the operation of relay 831. Since relay 521 is not energized, no path is found for battery through low resistance 915 to the impulse circuit and only a weak impulse is transmitted. Due to this weak impulse, relay 601 is operated, shunting relay 609 which relay releases. When relays 807 and 808 deenergize, relay 810 operates, causing the release of relays 813 and 812, 814 and 815 and in turn the release of relays 811 and 810. The release of relay 812 deenergizes relay 601 opening the circuit of relay 608 and permitting relay 625 to operate in series with relay 626.

Relay 831 remains locked in a circuit including its right winding and contact, conductor 842, inner upper contact of relay 512 to ground. The release of relay 814 permits relay 520 to energize in series with relay 512. Relay 520 closes a circuit from grounded battery, winding of relay 411, conductor 442, uppermost contact of relay 520 to ground. Relay 411 operates in this circuit and locks to grounded conductor 420. Relay 411 in operating opens the circuit of relay 400 which relay releases. After an interval, relay 404 is released, in turn releasing relay 410. The release of relay 410 removes ground from conductors 417, 420, 426

and 430 whereupon the sender selector switch 110 and all energized relays in the sender and registers are restored to normal. Thus the register sender is disconnected and may 5 be taken for use in connection with other calls.

When the sender is released and ground potential is removed from conductor 420, relay 203 becomes deenergized. Relay 203 10 releases and extends the tip and ring conductors of the trunk 103 through to the left winding of the repeating coil 201. Relay 202 is now operated in series with the calling line and closes a substitute holding circuit 15 for the slow relay 204. In this manner the release of the connection is placed under the control of the subscriber's switchhook. Relay 203, in releasing, also opens the holding circuits of relays 205 and 206. Relay 206 20 releases and extends the tip and ring conductors of the trunk 207 through to the right windings of repeating coil 201.

Returning to the call indicator apparatus in the distant office, at the time relay 625 25 operates, a circuit is closed from ground through the outer left contact of said relay, contact of relay 636, winding of relay 607, to battery. Relay 607 operates and opens to battery. Relay 607 operates and opens the 30 circuit of relays 305 and 312. Relay 305 extends the tip and ring conductors of the trunk 207 through to the left windings of repeating coil 313, whereupon the following circuit is completed: battery, through the inner lower 35 contact of relay 300, conductor 301, right winding of relay 302, winding of relay 303, inner normal contact of relay 304, thence over the tip side of the line through the upper right winding of repeating coil 201, winding 40 of polarized relay 214, lower right winding of coil 201 and returning over the ring side of the line through the outer normal contact of relay 304, left winding of relay 302 to ground. Relay 302 operates, causing, 45 in turn, the operation of relay 306.

At the time relay 620 operates it closes an obvious circuit for relay 627. When the relay 627 energizes circuits are completed for lighting the numerical lamps in 50 accordance with the digits recorded on the register relays in Fig. 7. Since the numerical designation is 2 5 3 1 the No. 2 thousands lamp 707 is illuminated in a circuit from battery, through the lower right contact of relay 627, conductor 628, inner 55 right back contact of relay 708, left front contact of relay 700, inner left back contact of relay 709, lamp 707, outer right front contact of relay 700, outer left contact of relay 709, outer right back contact of relay 710, conductor 711, lower left contact of relay 627 to the grounded conductor 613. Also a circuit is closed from battery through 60 the upper right contact of relay 627, conductor 629, lamp 712, left back contact of

relay 713, outer right back contact of relay 714, left back contact of relay 715, inner left front contact of relay 703 to ground over conductor 701. Moreover, another circuit is closed from battery through the outer 70 right contact of relay 626, conductor 630, inner right back contact of relay 716, left front contact of relay 705, inner left front contact of relay 704, lamp 717, inner left back contact of relay 716 to the grounded 75 conductor 702. Lastly, a circuit is closed from battery through the right front contact of relay 625, conductor 631, inner right back contact of relay 718, left back contact of relay 719, outer right front contact of 80 relay 706, lamp 720, outer left contact of relay 718 to ground over conductor 702.

The operator reads the number from the lamps of the call indicator, seizes the plug 85 314 and inserts it in the jack 315 of the 85 called line 319. A circuit is now closed from ground through the sleeve relay 317, sleeve of the jack 315, sleeve of plug 314, winding of relay 300, outer right contact of relay 306, which is operated at this time, 90 contact of relay 316, inner back contact of relay 318, winding of relay 320 to battery. A branch of this circuit extends through the winding of relay 318, but this relay being shunted does not operate. A parallel circuit 95 is also closed through the disconnected lamp 321, but since lamp 321 is shunted it does not illuminate. Relay 300 operates and at its lowermost front contact closes a circuit for the upper winding of relay 308. 100 Relay 308 operates and opens the circuit of relays 605 and 309. Relay 309 disconnects the interrupter 311 from the lamp 307 and this lamp is extinguished. Relay 605 removes ground from the conductors 611 and 105 702 causing the release of all relays and the extinguishment of all illuminated lamps in the call indicator mechanism.

Relay 320 operates in the circuit above traced and closes a circuit from the source 110 of ringing current through the marginal relay 316, lower front contact of relay 320, ring of the plug and jack, thence over the subscriber's line and returning through the tip of the jack and plug, upper front contact of relay 300, upper front contact of relay 320 to ground. When the subscriber responds to the ringing of his bell, the marginal relay 316 operates; removes the shunt and permits relay 318 to become energized. Relay 318 closes a circuit from battery through its inner front contact and winding and thence to ground through the sleeve relay 317, whereby relay 320 is 115 shunted out and releases. Relay 320 completes the tip and ring conductors through to the right windings of the repeating coil 313. Relay 322 operates in series with the called line and closes an obvious circuit for relay 304. Relay 304 serves to reverse the 120 125 130

current over the line and also to include the left winding of repeating coil 313 in the talking circuit.

After the conversation has finished, the 5 calling subscriber by replacing his receiver on the switchhook opens the circuit of relay 202, which in turn, opens the circuit of relay 204. After an interval relay 204 releases 10 and removes ground from conductor 111 whereby the line switch 100 and the district switch 200 restore the connection.

When the trunk at the mechanical office is released the circuit of relay 302 in the 15 distant office is opened and the relay 306 consequently releases. Relay 306 at its outer right contact removes the shunt from around the lamp 321 and this lamp illuminates to advise the operator that the connection is no longer required. She, thereupon, withdraws the plug 314 from the jack 315 and all energized relays associated with 20 the cord circuit are released.

It has thus been explained how the 25 impulse generating equipment associated with the register sender in the mechanical office creates and transmits codes of impulses representing digits recorded on the registers to affect apparatus in the distant exchange. While only the four numerical digits characterizing the line number have been 30 considered in this system it will be understood of course, that the same mechanism may be employed for transmitting as many other digits as are necessary for the particular 35 type of system concerned and for which registers are provided.

What is claimed is:

1. In an impulse transmitting system, an 40 impulse transmitting circuit, a source of current circuits for applying said source of current to said impulse circuit to produce current of definite strength thereover, means to intermittently reverse the connections from said source of current to said impulse 45 circuit, means comprising circuits in parallel with said last-mentioned circuits effective to either increase or decrease the strength of said current, depending upon the side of the impulse circuit to which said source of current 50 is connected.

2. In an impulse transmitting system, an impulse transmitting circuit including a source of potential, means to repeatedly reverse the connection of said source of potential to said circuit to produce pulses of alternate polarity and definite strength, branch circuits, means to extend said branch circuits in a predetermined order to include means for either increasing or decreasing the strength of said pulses, and means for rendering said circuits effective according to the side of said impulse circuit to which said source of potential is 60 connected.

3. In an impulse transmitting system, an

impulse transmitting circuit including a source of potential, reversing means, means for operating said reversing means to repeatedly reverse the connection of said source of potential to said circuit to produce 70 pulses of alternate polarity and definite strength, branch circuits, means for extending said branch circuits in a predetermined order to include means for either increasing or decreasing the strength of said pulses, and 75 means to render said branch circuits effective to either increase or decrease the strength of said pulses in accordance with the operated or non-operated condition of said reversing means. 80

4. In a code impulse transmitting system, an impulse transmitting circuit including a source of potential, a control device, means to operate said control device, means to repeatedly reverse the connection of said source of potential to said circuit to produce 85 pulses of alternate polarity and definite strength, a plurality of branch circuits, means to extend said branch circuits in accordance with the setting of said control device to include means for either increasing or decreasing the strength of said pulses, and means to render said branch circuits effective according to the side of said impulse circuit to which said source of potential 90 is connected. 95

5. In an impulse transmitting system, an impulse transmitting circuit including a source of potential, a time measuring device, means under the control of said time measuring device to repeatedly reverse the connection of said source of potential to said circuit to produce pulses of alternate polarity and definite strength, a plurality of branch circuits, means to extend said branch 105 circuits in a predetermined order to include means for either increasing or decreasing the strength of said pulses, and means to render said branch circuits effective according to the side of said impulse circuit to 110 which said source of potential is connected.

6. In an impulse transmitting system, a loop impulse transmitting circuit, means for generating and transmitting impulses of alternate polarity over said loop circuit, and means to selectively ground both sides of said loop circuit to prevent the transmission 115 of certain one of said pulses.

7. In an impulse transmitting system, a loop impulse transmitting circuit, a control 120 device, means for generating and transmitting impulses of alternate polarity over said loop circuit, and means to operate said control device to selectively ground both sides of said loop circuit to prevent the transmission 125 of certain ones of said pulses.

8. In a code impulse transmitting system, a loop impulse transmitting circuit, a register, means for setting said register, means for transmitting positive and negative im- 130

pulses over said impulse circuit, branch circuits, means for extending certain of said branch circuits to include means to increase the strength of said negative pulses, other branch circuits, means for extending other of the said branch circuits to connect ground to both sides of said impulse circuit to pre-

vent the transmission of positive pulses, and means to render said branch circuits effective under the control of said register. ¹⁰

In witness whereof, I hereunto subscribe my name this 16th day of October A. D., 1923.

OWEN C. FROM.
